FIRING RATE CONTROL MECHANISM
FOR AUTOMATIC FIREARMS

Antoine Gazda, Providence, R. I.

Application June 27, 1944, Serial No. 542,272
In Switzerland August 19, 1938

6 Claims. (Cl. 89—129)

1

The present invention relates to a new and improved recoil and return spring mechanism for the breech block of an automatic firearm, more especially a firearm of the so-called "blow-back" type, wherein the breech block is forced rearwardly by the explosion of the charge in the cartridge against the inertia of the parts and the recoil and return spring mechanism, the relationship of the parts being such that the rearward movement of the breech block effects a tensioning of the springs of the spring mechanism whereby the block is returned for firing the next shot.

A primary object of the present invention is the realization of simple but effective means associated with and constituting part of the said spring mechanism, whereby the firing rate of the firearm may be readily regulated.

A further object of the invention is the realization of a simple but effective means associated with and constituting part of said spring mechanism, whereby the recoil force of the latter may be regulated.

To these ends, briefly stated, means is provided whereby the mass of the rotary parts of the spring mechanism may be controlledly varied, and additional means is provided for regulably controlling the initial tension or preload of the spring mechanism.

Additional objects and advantages of the present invention will appear from the following detailed description of presently-preferred illustrative embodiments thereof, reference being made in this regard to the accompanying sheets of drawing wherein:

Fig. 1 is a top plan view of the firearm, with parts shown in longitudinal section;

Fig. 2 is a top plan view of the rear portion of the firearm on a relatively enlarged scale, parts being shown in longitudinal section;

Fig. 3 is a sectional view along line 3—3 of Fig. 2;

Fig. 4 is a fragmentary sectional view showing the spring mechanism unloaded mounted in a casing of modified form;

Fig. 5 is a view corresponding to Fig. 4 but showing the spring mechanism as pre-loaded;

Fig. 6 is a sectional view through one form of flywheel mass; and

Fig. 7 is a sectional view through another form of flywheel mass.

The firearm comprises the usual barrel 10, breech tube 11, and breech block 12 reciprocably mounted in the breech tube 11. The return and recoil spring mechanism comprises two housings

2

13 fixed on opposite sides, as viewed from the top, of the tube 11, each containing a toothed annulus 14 rotatably mounted on a stud 15 adjustably secured to its housing 13, as hereinafter described. Each toothed annulus 14 is in mesh with one of two gear racks 18 on the breech block 12 through slots in the tube 11. Inside each annulus 14 is arranged a spiral spring 19, the inner end of which is attached to the respective stud 15 and the outer end of which is secured to the annulus 14. The spiral springs 19 are arranged so that they coil in opposite directions and tend to move the breech block 12 forwardly toward the barrel 10 by means of the two toothed annuli 14.

When using the firearm according to the invention, the breech block 12 is drawn back in the usual manner until it is locked by a conventional trigger-releasable locking device (not shown) which holds it in its rear loading position (Fig. 2). During this movement of the breech block 12 into the loading position, both spiral springs 19 are tensioned. Simultaneously a cartridge from the cartridge magazine (not shown) is introduced in front of breech block 12. When the above-mentioned locking device is released, the breech block 12 is moved forward by the two spiral springs 19 whereby the cartridge is moved into the loading chamber to be fired immediately thereafter. The block 12 is again forced back against the action of the two spiral springs 19 by the pressure of the gases resulting from the explosion, whereupon the above described firing action is repeated. In order to damp the recoil of the breech block 12, a buffer in the form of a helical spring 20 or the like may be provided.

Threadedly or otherwise suitably secured to each annulus 14 on each side thereof is a disc-like cover plate 21 or 22, interposed between the central flange 23 of which and the stud 15 are antifriction bearings 24. The cover plates 21 and 22 are of different configuration and weight and thus severally constitute a variable flywheel mass 45 which makes it possible to regulate the firing rate of the gun by the simple expedient of changing the respective cover plates 21, 22. The two flywheel masses 21 and 22 which have been illustrated are solely exemplary in character and 50 a plurality of such masses, of varying magnitude, may be provided. Two similar masses 24 may be used on each annulus 14, or the latter may be associated with two dissimilar masses as shown.

Keyed to one end of each stud 15 is a lever 25, 55 the free end of which carries a spring-pressed

plunger 26 adapted to be received in any one of a plurality of recesses 27 provided in the casing 13. Knob 28 is provided for withdrawing the plunger 26 from a recess and, after rotating the lever 25 to correspondingly tension or pre-load the spring 19, for re-inserting the same in the recess 27 corresponding to the pre-load position. The other end of each stud 15 carries a cap 17 secured here-to by pin 17', as shown. When the plunger 26 is in the first recess 27, there is no preload. Fig. 10 shows the spring 19 without pre-load, while Fig. 5 shows the spring in a pre-tensioned or pre-loaded state.

A modified form of casing 13a is shown in Figs. 4 and 5, the recesses 27 being formed in an outwardly projecting flange 29. In any event, recesses 27 are concentrically arranged with respect to stud 15. In firing the first round, the breech block 12 is, of course, drawn back against the action of the springs 19. Stud 15 is, in effect, a fixed abutment as long as plunger 26 remains in engagement with any recess 27 in the housing 13.

The possibility of effecting the pre-loading of the springs 19 makes it possible to regulate the recoil force with the different firing rates obtained through the different flywheel masses, and thus to realize the objects of the invention.

The present application is in part a continuation of abandoned copending application, Serial No. 289,661, filed August 11, 1939, for "Automatic firearms."

Having thus disclosed the invention, what is claimed is:

1. In an automatic firearm, a barrel, a breech tube secured to said barrel, a breech block slideable in said breech tube, a pair of spiral recoil springs, a rack upon said breech block associated with each spring, a gear cooperating with each rack having one end of the associated recoil spring fixed thereto, a casing for each gear and associated spring fixed to said tube, a plate detachably connected to said gear whereby said plate may be replaced by another plate of different mass to vary the firing rate of the firearm, a fixable abutment extending axially through said gear to which the other end of each spring is connected, a lever connected to said abutment and means for connecting said lever selectively at any one of a plurality of spaced points upon said casing to vary the initial tension of the associated recoil spring.

2. In an automatic firearm, a barrel, a breech tube secured to said barrel, a breech block slideable in said breech tube, a spiral recoil spring located upon each side of said breech block, a rack upon said breech block associated with each spring, a gear cooperating with each rack, a casing enclosing each gear and associated spring fixed to said tube, each spring being connected to the gear associated therewith and to said casing, and a pair of plates anti-frictionally mounted and threadedly connected to each gear whereby said plates may be replaced by other plates of different mass thereby varying the firing rate of said firearm.

3. In an automatic firearm, a barrel, a breech tube secured to said barrel, a breech block slideable in said breech tube, a pair of spiral recoil springs located upon opposite sides of said breech block, a fixable abutment associated with each spring to which one end of the associated spring is connected, a gear also associated with each spring to which the other end of said spring is connected, a pair of racks on said breech block adjacent said springs and cooperating with said

gears whereby the breech block is always urged in a forward direction and the recoil is diffused through said springs, means fixed to said breech tube and completely encasing each spring and associated abutment and gear, a detachable weight rotatably mounted on said abutment and secured to each gear whereby different weights may be attached to each gear to vary the firing rate, a lever connected to said abutment and means connecting said lever selectively to any one of a plurality of spaced points upon said encasing means to vary the positioning of said abutment and thereby the initial tension of the associated recoil spring.

4. In an automatic firearm, a barrel, a breech tube secured to said barrel, a breech block slideable in said breech tube, a pair of spiral recoil springs located at opposite sides of said breech block, an annular exteriorly toothed gear associated with each of said springs having one end of the spring associated therewith secured thereto, racks upon said breech block cooperating with said gears, a casing fixed to said breech tube for each spring and associated gear, an abutment mounted in said casing to which the other end of each associated spring is secured, detachable cover plates rotatably mounted on said abutment secured to each annular gear enclosing the spring associated therewith whereby said cover plates may be detached and replaced with cover plates of different mass to vary the firing rate.

5. In an automatic firearm, a barrel, a breech tube secured to said barrel, a breech block slideable in said breech tube, a pair of spiral recoil springs located at opposite sides of said breech block, an annular exteriorly toothed gear associated with each of said springs having one end of the spring associated therewith secured thereto, racks upon said breech block cooperating with said gears, a casing fixed to said breech tube for each spring and associated gear, an abutment mounted in said casing to which the other end of each associated spring is secured, detachable cover plates rotatably mounted on said abutment secured to each annular gear whereby said cover plates may be detached and replaced with cover plates of different mass to vary the firing rate, a lever fixed at one end to said abutment, a spring actuated plunger mounted at the other end of said lever and said casing having a plurality of spaced apertures with which said plunger cooperates to fix said abutment in a plurality of positions to vary the initial tension of said recoil springs.

6. In an automatic firearm, a barrel, a breech tube secured to said barrel, a breech block slideable in said breech tube, a pair of spiral recoil springs located at opposite sides of said breech block, an annular exteriorly toothed gear associated with each of said springs having one end of the spring associated therewith secured thereto, racks upon said breech block cooperating with said gears, a casing fixed to said breech tube for each spring and associated gear, an abutment mounted in said casing to which the other end of each associated spring is secured, detachable cover plates rotatably mounted on said abutment secured to each annular gear whereby said cover plates may be detached and replaced with cover plates of different mass to vary the firing rate, a lever fixed at one end to said abutment, a spring actuated plunger mounted at the other end of said lever, said casing having a plurality of spaced apertures with which said plunger cooperates to fix said abutment in a plurality of posi-

tions to vary the initial tension of said recoil springs and anti-friction means located between said plates and said abutment.
